Atts.

UNITED STATES PATENT OFFICE.

GEORGE P. BOSWORTH, OF CENTRAL FALLS, RHODE ISLAND, ASSIGNOR TO HEMPHILL COMPANY, OF CENTRAL FALLS, RHODE ISLAND, A CORPORATION OF MASSACHUSETTS.

STOCKING AND METHOD OF MAKING SAME.

Application filed July 26, 1922. Serial No. 577,717.

To all whom it may concern:

Be it known that I, GEORGE P. BOSWORTH, a citizen of the United States, and a resident of Central Falls, in the county of Providence and State of Rhode Island, have invented an Improvement in Stockings and Methods of Making Same, of which the following description, in connection with the accompanying drawings, is a specification, like characters on the drawings representing like parts.

This invention relates to stockings and to the method of making the same. In order that the principle of the invention may be readily understood, I have disclosed in the drawing a single embodiment of the stocking and will describe the best mode known to me for making the same.

The drawing represents a side elevation 20 of a stocking constructed in accordance with my invention.

The stocking may be begun at the top 1 of the leg or at the top 2 of the toe. I will first describe the stocking as knitted beginning at the top 1 of the leg upon a circular series of needles which may be of any type, but which preferably are spring beard needles mounted for independent reciprocation in the grooves of the needle cylinder of any suitable machine, such, for example, as a Banner machine adapted to knit split foot stockings but equipped with means to effect the special operations hereinafter set forth. Within the scope of my invention said operations may be practised manually. Any suitable number of needles may be employed and the relative numbers thereof used in knitting the different parts may be varied. The numbers hereinafter given are by way 40 of example merely.

It will be assumed that the knitting is commenced upon a circle of 240 needles, and is continued down by rotary knitting to the line A—A, which although of the irregular direction shown, in the completed stocking, is while the stocking is in the machine a transverse line directly across the stocking. I then throw out the front half of the needles, 120 in number in the present example, from a point 3 to a corresponding point upon the opposite side of the stocking, said needles retaining their loops. I at the same time throw out of action 96 additional needles (48 on each side) in the present ex-

ample, extending on one side from the point 3 to the point 4 and on the other side of the stocking extending between similar points, said 96 needles retaining their loops. This leaves in action only 24 needles in the present example, symmetrically arranged at the back of the leg and extending from the point 4 around to a corresponding point on the opposite side of the stocking. I then begin to knit on said 24 needles and I constantly widen at each end of each stroke of reciprocation in a well known way. Desirably I do this upon a Banner machine by throwing up one needle at each end of each reciprocatory stroke and throwing down two needles, thus giving an actual widening of one needle at each end. For the best results, such widening is effected at each end of each reciprocation, though my invention is not limited to effecting the widening upon each reciprocation.

The widening is continued until upon both sides of the stocking the said 96 needles are all brought into action, thus making a gore extending on each side from one end of the line A down to a line B—B and indicated at 5. This provides an actual fullness in the calf of the leg. If desired, the gore 5 may be located at a higher point in the calf.

I then immediately bring into action the front 120 needles, which up to this time have retained their loops and then I knit by reciprocating knitting upon the entire circle of needles, using two yarn guides, one feeding to the front half of the needles, 120 in number to make the front of the ankle indicated at 6, and the other yarn guide feeding to the back half of the needles, 120 in number, to make the back half 7 of the ankle, the said two portions knitted by reciprocating knitting being joined by two suture lines or seams, (one of which is indicated at 8) characteristic of split foot work and which therefore need not be more fully described. Desirably when I begin knitting the gore 5 I substitute or introduce a different yarn which is preferably heavier, though desirably both the yarn or thread by which the main portion of the leg and the front of the ankle is knitted, as well as the yarn by which the gore 5 in the back of the ankle are knitted are composed of silk in the gum and which is boiled out after the stocking is made. At a suitable point, as

for example at the point 7^a I substitute or add a high splice yarn to form the high splice indicated at 7^b.

The knitting is continued in accordance 5 with the usual practice of split foot work until a line C.C.C is reached, whereupon the instep needles are thrown out of action while retaining their loops and the heel portion 9 is knitted by narrowing and widening in a 10 usual manner, but desirably upon a heel yarn which is substituted for the yarn by which the portions 5 and 7 and 7^b are knitted, and which as hereinafter stated may themselves differ. After the heel pocket is completed, 15 the instep needles are restored to action and then the foot is knitted by split foot work so as to make on each side of the foot a suture line or seam, one of which is shown as extending from the point 10 to the point 11. The top of the foot is knitted 20 desirably from the same yarn used to knit the upper portion of the leg and the front ankle portion 6, but the bottom of the stocking indicated at 12 is desirably knitted from 25 the same yarn or thread used for the heel, which is preferably a mercerized yarn. Desirably at the end of the upper portion of the foot I knit circularly upon all the needles to form the portion 13, using the yarn em- 30 ployed for knitting the bottom of the foot, and thereafter I knit the toe pocket 14 in the usual manner by narrowing and widening.

After the stocking has been knitted, it is preferably boiled to remove the gum 35 from the silk and may be dried upon a forming board.

Instead of beginning the operation at the top of the leg the operation may be reversed and the knitting begun upon one half the 40 needles extending from a point 15 at the toe around to a corresponding point on the opposite side and the procedure described is reversed until the horizontal line A, B, B is reached, whereupon I throw out of 45 action the front half of the needles, 120 in number, permitting them to retain their loops, and then I knit by reciprocating knitting upon the remaining half of the needles but narrow at each end of each 50 reciprocating stroke,—that is, I throw one needle up out of action at each end of each reciprocating stroke, but permitting the needle to retain its loop. This narrowing operation I continue until at each side of 55 the stocking, I have thrown out of action 48 needles, thus leaving in action 24 needles, I then immediately bring into action by a single movement of the machine the two groups of 48 needles each and the front half 60 of the needles, 120 in number, whereupon I continue the knitting upon all the needles, but knit by rotary work until the top 1 of the leg is reached.

It will be observed that the lines 3, 4 at 65 opposite sides of the stocking are at the calf

of the leg and at substantially the point where the fashioning occurs in a full fashioned stocking. Therefore in addition to the actual formation of the gore 5 which supplies additional material to the stocking 70 and makes an actual fashioning, there is a general simulation of the full fashioned effect, which taken in conjunction with the split foot work used in forming the ankle results in a stocking having very desirable 75 characteristics.

Desirably I change the stitch length when I begin to knit upon the 24 needles according to the first method, shortening the 80 stitches, and when I throw into action the front half of the needles I resume the knitting thereon with a shorter loop. In other words from the line A A downward the 85 knitting is effected by smaller loops, thus giving something of a shaping to the stocking. I desirably shorten the stitch length at a plurality of points below the line A A. I reverse this in knitting in accordance with the second method. I may and desirably do use different weights or colors or both of 90 yarn at the front and the back of the ankle part, as by using heavier yarn at the back, and I may in knitting the gore 5 use a yarn somewhat heavier than the yarn for knitting the upper part of the leg and the front 6 95 of the ankle, and then change to a still heavier yarn for knitting the back portion 7 of the ankle and to a still heavier yarn for knitting the high splice 7^b.

I do not in this application disclose or 100 claim the subject matter of my co-pending application S. N. 577,871, wherein is disclosed and claimed a stocking having among other features a gore at substantially the 105 position of a tapered high splice and the method of making such a stocking.

Having thus described one illustrative embodiment of my invention and the best method known to me for carrying out the 110 same, I desire it to be understood that although I have used specific terms they are employed in a generic or descriptive sense and not for purposes of limitation, the scope 115 of the invention being set forth in the accompanying claims.

I claim:

1. A seamless stocking having a circularly knit, upper leg portion, a gore at the calf portion, a split work ankle integrally knitted with said gore and leg portion and as an immediate continuation thereof, and a foot integral with the ankle portion.

2. A seamless stocking having a circularly knit, upper leg portion, a gore at the calf portion, a split work ankle integrally knitted with said gore and leg portion and as an immediate continuation thereof and a split foot integral with the ankle portion.

3. A seamless stocking having a circularly knit, upper leg portion, a gore at 130

- the calf portion respectively having a varying number of loops in successive courses, a split work ankle integrally knitted with said gore and leg portion and as an immediate continuation thereof, and a foot integral with the ankle portion.
4. A seamless stocking having a circularly knit, upper leg portion, a gore at the calf portion, a split work ankle integrally 50 knitted with said gore and leg portion and as an immediate continuation thereof, and a foot integral with the ankle portion, the front and back portions of the ankle being composed of contrasting yarns.
- 10 5. A seamless stocking having a circularly knit, upper leg portion, a gore at the calf portion respectively having a varying number of loops in successive courses, a split work ankle integrally knitted with 55 said gore and said leg portion and as an immediate continuation thereof, the seam at each side of the gore meeting the top of the ankle suture seams, and a foot integral with the ankle portion.
- 20 6. A seamless stocking having a circularly knit, upper leg portion, a gore at the calf portion respectively having a varying number of loops in successive courses, a split work ankle constituting an immediate 60 continuation of said gore and the corresponding front leg portion, the suture seams whereof meet the seams of the gore, and a foot.
- 25 7. That method of knitting a seamless stocking comprising knitting a tubular, upper leg portion, then reciprocatingly knitting a gore with a varying number of needles in successive courses, then immediately knitting an ankle portion by split work with 65 separate yarns, and then knitting a foot.
- 30 8. That method of knitting a seamless stocking comprising knitting the upper leg portion by rotary knitting, then throwing out of action while retaining their loops 70 the front half of the needles and all of the remaining needles except a relatively small number symmetrically arranged at the back of the leg, then reciprocatingly knitting a gore as an integral continuation of the upper leg portion, and successively increasing 75 the number of needles in successive courses, thereby restoring to action the rear needles temporarily placed out of action, then restoring to action the front half of the needles, then immediately knitting the ankle portion by split work with separate yarns, and then knitting a foot.
- 40 9. That method of knitting a seamless stocking comprising knitting by tubular work the upper leg portion, then throwing out of 80 action while retaining their loops the front half of the needles and all of the second half excepting a relatively small number symmetrically positioned at the back of the leg, 85 then knitting reciprocatingly a gore upon 90 the needles in action and the successively restored, remaining, rear half of the needles, thereby producing a tapering seam, then restoring to action the front half of the needles, then upon separate yarns immediately knitting by split work the front and back of the ankle, and then integrally with the ankle knitting a heel, a split foot and a toe.
- 10 10. Those steps in the knitting of a seamless stocking upon a circular series of needles which comprise throwing out of action while retaining their loops a group of needles at the front of the stocking at the calf portion thereof, and then upon the remaining 95 needles knitting a gore composed of partial courses, and thereafter bringing into action all the needles and knitting split work thereon as an immediate continuation of said gore and the corresponding front part of the stocking.
11. Those steps in the knitting of a seamless stocking upon a circular series of needles which comprise throwing out of action while retaining their loops a group of needles at the front of the stocking at the calf portion thereof, and then upon the remaining needles knitting a tapered gore composed of partial courses of varying length and thereafter bringing into action all the needles and knitting split work thereon as an immediate continuation of said gore and the corresponding front part of the stocking.
12. A seamless stocking having a circularly knit, upper leg portion, a gore at the calf portion thereof composed of additional partial courses, a split-work ankle integrally knitted with said gore and leg portion, and a foot integral with the ankle portion.
13. A seamless stocking having a circularly knit, upper leg portion, a gore at the calf portion composed of additional partial courses varying in length, a split-work ankle integrally knitted with said gore and leg portion and as an immediate continuation thereof, and a foot integral with the ankle portion.
14. A seamless stocking having a circularly knit, upper leg portion, a gore at the calf portion, the wales whereof are all continuations of wales in the tubular part of the upper leg portion, a split-work ankle integrally knitted with said gore and leg portion and as an immediate continuation thereof, and a foot integral with the ankle portion.
15. A seamless stocking having a circularly knit, upper leg portion, a gore at the calf portion composed of additional partial courses having respectively a varying number of loops in successive courses, a split-work ankle integrally knitted with said gore and leg portion and as an immediate continuation thereof, and a foot integral with the ankle portion.

16. A seamless stocking having a circularly knit, upper leg portion, a gore at the calf portion composed of additional partial courses having respectively a varying number of loops in successive courses, a split-work ankle integrally knitted with said gore and said leg portion and as an immediate

continuation thereof, the seam at each side of the gore meeting the top of the ankle suture seams, and a foot integral with the ankle 10 portion.

In testimony whereof, I have signed my name to this specification.

GEORGE P. BOSWORTH.
